[57] CLAIM

The ornamental design for a wrench for releasing a vacuum seal on a water pump or the like, as shown.

DESCRIPTION

FIG. 1 is a perspective view of a wrench for releasing a vacuum seal on a water pump or the like showing my new design;

FIG. 2 is an enlarged side elevational view thereof;

FIG. 3 is an enlarged bottom plan view thereof;

FIG. 4 is an enlarged opposite side elevational view thereof;

FIG. 5 is an enlarged top plan view thereof;

FIG. 6 is an enlarged end elevational view thereof; and

FIG. 7 is an enlarged opposite end elevational view thereof.

FIG. 1.

FIG. 2.

FIG. 3.

FIG. 4.

FIG. 5.

FIG. 6.

FIG. 7.
